UNITED STATES PATENT OFFICE.

BAINBRIDGE W. BURDICK, OF ALBANY, NEW YORK.

DESIGN FOR A FOUNDER'S CORE-SUPPORTING SHELL.

SPECIFICATION forming part of Design No. 28,763, dated May 31, 1898.

Application filed March 4, 1898. Serial No. 672,609. Term of patent 14 years.

To all whom it may concern:

Be it known that I, BAINBRIDGE W. BURDICK, a citizen of the United States, residing at Albany, in the county of Albany and State 5 of New York, have invented and produced a new and original Design for Founders' Core-Supporting Shells, of which the following is a specification, reference being had to the accompanying drawings, forming part thereof.

10 Figure 1 is a perspective view of a founder's core-supporting shell, showing my new design viewed from its outer side. Fig. 2 is a perspective view of the same viewed from its inner side. Fig. 3 is a view from its lower 15 side.

As shown in the drawings, the leading and material features of my design consist in a shell having the shape or configuration comprising a perforated horizontal circular face 20 side A and a series of lateral sides B, separated by openings and terminating at their lower ends in angularly-projected flanges b, all disposed or arranged as shown, the horizontal circular face side A having a plain flat 25 upper surface bounding its perforation a, as shown in Fig. 1, and the lateral sides B having their respective outer surfaces convex in

a horizontal direction and running vertically from the circumferential line of said circular face side A and terminating in plain flanges 30 b, which have their upper surfaces at an angle to the vertical lines of the convex outer surfaces of said sides B, as shown in Fig. 1. The outer surfaces of the sides B are left plain, and the openings C, separating said 35 sides, as shown in the several figures, are extended from the lower ends of the latter up to within a short distance from the circumferential line of the horizontal face side A and terminate at the lower edges of the shorter 40 convex lateral side portions B', which respectively are integral with both the horizontal circular face side A and adjoining two lateral sides B, as shown.

Having described my invention, what I 45 claim as new, and desire to secure by Letters Patent, is—

The design for a founder's core-supporting shell as herein shown and described.

BAINBRIDGE W. BURDICK.
